UNITED STATES PATENT OFFICE.

RAYMOND H. DIETRICH, OF DETROIT, MICHIGAN, ASSIGNOR TO DIETRICH INCORPORATED, OF DETROIT, MICHIGAN, A CORPORATION OF MICHIGAN.

DESIGN FOR AN AUTOMOBILE BODY.

Application filed August 15, 1927. Serial No. 23,095. Term of patent 14 years.

To all whom it may concern:

Be it known that I, RAYMOND H. DIETRICH, a citizen of the United States of America, residing at Detroit, in the county of Wayne and State of Michigan, have invented a new, original, and ornamental Design for Automobile Bodies, of which the following is a specification, reference being had to the accompanying drawing, forming part thereof.

Fig. 1 is a side elevation of an automobile body embodying my invention; Fig. 2 is a section on the line 2—2 of Fig. 1; and Fig. 3 is a section on the line 3—3 of Fig. 1.

The automobile body is provided with horizontal moulding portions below the window openings and upwardly extending moulding portions along the sides of the window openings, so that a low appearance is given to the body.

I claim:

The design for an automobile body as shown and described.

RAYMOND H. DIETRICH.
